UNITED STATES PATENT OFFICE.

HENRY A. WISE WOOD, OF NEW YORK, N. Y., ASSIGNOR, BY MESNE ASSIGNMENTS, TO WOOD NEWSPAPER MACHINERY CORPORATION, OF NEW YORK, N. Y., A CORPORATION OF VIRGINIA.

MACHINE FOR FINISHING AND COOLING STEREOTYPE-PLATES.

1,134,798.

Specification of Letters Patent.

Patented Apr. 6, 1915.

Application filed September 28, 1908. Serial No. 454,972.

To all whom it may concern:

Be it known that I, HENRY A. WISE WOOD, a citizen of the United States, residing at New York, in the county of New York and 5 State of New York, have invented a new and useful Machine for Finishing and Cooling Stereotype-Plates, of which the following is a specification.

This invention relates to machines for finishing stereotype printing plates, and particularly to that type thereof in which the plates are fed along substantially in a straight path, and preferably down an incline into position to be cooled. 10 While the features of this invention are capable of general use, it is herein presented more as an improvement on certain previous inventions on which I have filed applications for United States patents as 15 follows:—“Machine for finishing and cooling stereotype plates,” filed April 6, 1905, Serial No. 310,343, and “Gravity shaving and cooling machine for stereotype plates” filed Aug. 9, 1906, Serial No. 329,833.

15 The principal objects of this invention are to provide improved means for raising the curved plate into an arch where it is to be shaved, and means for simultaneously springing the edges of the plate inwardly so as to bring it into small diameter, whereby the face of the plate will not rub against the arch and be battered while being raised, and to provide for allowing the edges to resume normal condition when in the arch; 20 also to provide for properly adjusting the distance the plate is raised on both sides; to provide for conveniently and effectively lowering the plate out of the arch; and generally, to improve and simplify the construction and operation of stereotype plate shaving machines.

Further objects and advantages of the invention will appear hereinafter.

Reference is to be had to the accompanying four sheets of drawings in which—

Figure 1 is a side elevation of a gravity shaving machine constructed in accordance with the present invention; Fig. 2 is a longitudinal sectional view of the same with 5 certain parts omitted. Fig. 3 is a side elevation of a portion of the same on an enlarged scale; Fig. 4 is a sectional view on the line 4—4 of Fig. 3. Fig. 5 is a sectional view on the line 5—5 of Fig. 3 with cer-

tain parts omitted, showing certain parts in 55 elevation. Fig. 6 is a similar view showing the left-hand side with the parts in another position; and Fig. 7 is a fragmentary view showing how one of the supporting rollers for the edge of the plate is operated. 60

Although this invention is not limited to the gravity type of shaving machines, it is particularly adapted thereto, and is shown as applied to that type. The machine is illustrated as embodying a frame 10 having an inclined top provided with a horizontal receiving table 11 at one end, and having an inclined run way formed by rollers 12 arranged on an incline for receiving the edges of the plates from the table 11. Located between these rollers is a saddle 13 over which the plates move, and at the end of which are located a set of cams on the longitudinal shaft 14 of the machine. Two of these cams numbered 15 and 16 will be 75 described hereinafter. The third cam 17 operates a roller 18 shown in Fig. 4, which is connected with a sliding stop 19, normally pressed by a spring 20 into a position to prevent the passage of the plate. As the 80 shaft 14 revolves this stop is drawn down and allows the plate to slide down the incline into the shaving arch 21, where it rests on rollers 22. In this arch is shown a stationary member or saddle 25 having a flat 85 steel spring 26 thereon for engaging the inner side of the plate and checking its downward motion as it approaches the discharge end thereof, so as to prevent its striking a stop 27 at the lower end with too much 90 force. The stop 27 is operated by a track cam 28 on the shaft 14 so as to come into proper position to stop the plate as it reaches the bottom or discharge end of the shaving arch. It will be understood that a shaving 95 blade 29 is mounted on the shaft 14 for shaving out the inside of the plate.

When the plate first rests on the rollers 22 these are at their lowermost position, and they are caused to carry the plate up into the 100 arch, in proper position to be shaved by the following mechanism: The cam 15 previously mentioned, operates a cam roller 30 mounted on a lever 31 and connected with an arm 32 on a rock-shaft 33. This rock-shaft carries a gear segment 34 operating a vertically sliding rack 35 which carries a support 36 on one side of the machine on

which one set of rollers 22 are mounted. In a similar way the cam 16 operates a rock shaft 37 on the other side of the machine which carries arms 38 connected by links 40 with a slid able member 410. A fixed member 41 carries adjustable rods 42, which, carry springs 43 that yieldingly force upwardly a support 44 on which are mounted the rolls 22 on the other side. It is to be observed that the limit of the rocking motion of the shafts 33 and 37 is capable of adjustment by means of studs 45 and pairs of set-screws 46 mounted on the two arms extending from the shafts and connected with the forked levers. The operation of the two rock shafts after the set screws are properly adjusted causes the plate resting on the two sets of rollers to be elevated the same distance on both sides, unless the plates differ in length, in which case the variation is taken up by the compression springs 43. Means is provided also whereby as the plate is raised, its lower edges are sprung inwardly so as to clear the sides of the arch to prevent the plate rubbing against the arch. The mechanism shown for accomplishing this result consists of levers 50 pivotally mounted on the supports 36 and 44. These levers are provided with springs 52 at the bottom which normally swing the lower ends inwardly and the upper ends outwardly. They are provided with cam rollers 53 adapted to engage stationary cams 54 on the sides of the machine. These cams are provided with a cut-out portion 55 at the bottom and a second less pronounced cut-out portion 56 further up. Between these cut-out portions the cam has a rise 57. On the upper ends of the levers 50 are located inwardly projecting gripping edges or jaws 58. As these parts are raised, the rollers 53 are forced inwardly by the cam 54 so as to cause the edges 58 to grip the edges of the plate outside the matter, and compress them toward each other. As the parts approach their uppermost position, the cam roller 53 drops into the top cut-outs 56, thus allowing the edges of the plate to spring back to fit the arch tightly, the plate being held in this position by the rolls 22 during the shaving operation. As the shaft 14 continues its rotation the cams 15 and 16 operate to lower the rolls 22 in an obvious manner and allow the parts to drop by their own weight, assisted by the weight of the plate. An extension spring 60 is provided connected with arms 61 extending from the two rock shafts, and having an adjustment 62 for the purpose of starting the parts downwardly if they stick or show any tendency to remain up. As the plate drops back the cams 54 cause the levers 50 to press the edges of the plate in so as to escape the sides of the arch and then release them, the plate being supported by the rollers all the

time. The cam 28 is so timed that when the plate drops back to its lowermost position, the stop 27 will be withdrawn so that the plate can slide along down over it. As the plate has had at the most only a preliminary cooling in the hollow arch, to and from which water flows through pipes 620, it is now fully cooled. 70

In order to prevent the wetting of the printing surface of the plate, and do away with the difficulty of drying the face of the plates thoroughly, the improper performance of which operation injures the rollers of the press, the following mechanism is provided: Surrounding the shaft 14 is a hollow semi-cylindrical cooling saddle 63 connected with a source of water supply by means of a series of pipes 64. The outer convex surface of this saddle is provided with perforations 65 and with a series of rifle grooves 66 running substantially horizontally, over which the water discharged from the inside runs in continuous unbroken streams, without producing a spray. The plate is cooled by said streams in an effective manner and no water is allowed to touch the printing surface. The water discharged from the cooling saddle passes down through the bottom of the machine where it is caught and discharged through a pipe 67. On the driving shaft 68 is a worm 78 operating a worm wheel 79 on the shaft 14. This worm is located in an oil casing 69. The end of the shaft 14 is shown as provided with an internal gear 70 meshing with a gear 71 on a shaft 72 journaled to rotate in the frame and provided with brackets 73 thereon carrying a drying device 74 for the interior of the plate. The supporting rolls continue to the bottom of the frame, and the plate brings up against a stationary stop 75 and is removed from the machine by hand or, in the absence of the stop, may be discharged on a table or truck located at the end of the machine. It will be understood of course that various shaving, trimming and other finishing means will ordinarily be employed with this machine. They are not shown herein as they are now well-known in the art and they can be applied easily to this machine in several ways, as for example, as shown in both of my prior applications mentioned above. 110

I do not herein claim the features of the cooling mechanism, the combination thereof with the finishing mechanism, or the method of cooling because these matters constitute a part of the subject matter of my co-pending divisional application Serial No. 557,107, filed April 23, 1910, entitled Machine for cooling stereotype plates. 120

While I have illustrated and described a preferred embodiment of the invention, and shown it as applied to a particular type of machine, I am aware that many modifica- 130

tions can be made herein and that it can be applied to many other types of machine without departing from the scope of the invention as expressed in the claims. Therefore I do not wish to be limited to all the features of construction shown, but

What I do claim is:—

1. In a machine for finishing curved stereotype printing plates, the combination 10 of a frame having an inclined upper surface, anti-friction rollers located along said frame in an inclined series, and a receiving table carried by the upper end of said frame and extending horizontally therefrom for receiving plates in position to be transferred to the rollers.

2. In a machine for finishing curved stereotype printing plates, the combination 20 of a saddle for receiving the plates, a longitudinal shaft, a shaving arch, means for arresting the plates before they enter the arch, and means on the shaft for operating said arresting means.

3. In a machine for finishing curved stereotype printing plates, the combination 25 with an arch, of a longitudinal shaft, cams on said shaft, forked levers engaging said shaft, a roller on each of said forked levers adapted to be operated by one of the cams, a pair of rock shafts, means connected with said rock shafts for moving the plates upwardly in the arch, and means for connecting said rock shafts with the forked levers.

4. In a machine for finishing curved stereotype printing plates, the combination 35 of a shaft, a cam on said shaft, a lever adapted to be operated by said cam, a rock shaft, means for adjustably connecting said lever with the rock shaft, and means operated by the rock shaft for raising the plates.

5. In a machine for finishing curved stereotype plates, the combination of a shaft, a pair of rock shafts, an arm connected with each rock shaft, a lever adapted to be operated by said first named shaft, means for adjustably connecting each lever with one of said arms, and connections from said rock shafts for raising the plates in the machine.

50 6. In a plate finishing machine, the combination of an arch for receiving the plates, supports for the opposite edges of the plates, means for yieldingly forcing one of said supports toward the arch, means for positively forcing the other support toward the arch a variable distance.

7. In a plate finishing machine, the combination of an arch for receiving plates, supports on the sides of the arch, rollers carried by said supports for supporting the edges of the plates, means for moving said supports toward the arch, and means for withdrawing them therefrom, said last named means comprising an adjustable spring connected with both support moving means.

8. In a plate finishing machine, the combination of movable supports for the edges of a plate, means for moving said supports, and means for springing the edges of the plate toward each other while resting on 70 said supports.

9. In a plate finishing machine, the combination of supports for the edges of the plates with means for forcing said edges toward each other on said supports. 75

10. In a plate finishing machine, the combination of an arch, means for moving plates toward the arch, and means for simultaneously springing the edges thereof so as to prevent them from rubbing against the arch. 80

11. In a plate finishing machine, the combination of an arch with means for simultaneously moving a plate into the arch and springing the edges thereof inwardly, and for releasing said springing means when the 85 plate is seated in the arch.

12. In a plate finishing machine, the combination of an arch with means for simultaneously moving a plate into the arch and springing the edges thereof inwardly, and 90 for releasing said springing means when the plate is seated in the arch, and for again springing said edges inwardly when the plate is being withdrawn.

13. In a plate finishing machine, the combination of an arch, means for moving the plates toward the arch, and a pair of levers located on the opposite sides of the arch for engaging the edges of the plate outside the matter when the plate is moved toward or 100 from the arch.

14. In a plate finishing machine, the combination of an arch, means for moving the plates toward the arch, a pair of levers located on the opposite sides of the plate for 105 engaging the edges of the plates outside the matter when the plate is moved, and cams located in position to engage said levers and operate them as they are raised or lowered with the plates.

15. In a plate finishing machine, the combination of a frame, an arch supported thereby, supports movably mounted on the frame for carrying the plate toward and from the arch, levers carried by said supports having jaws for engaging the edges of the plates, and cams fixed on the frame, said cams each having a cut out portion at the bottom for permitting the levers to swing backwardly away from the plates, a high 115 portion above said cut out portion for causing the levers to move inwardly so as to spring the plates, and a cut out portion at a higher level for permitting the levers to swing back, and the plate to assume a natural position in the arch. 120

16. In a plate finishing machine, the combination of a reciprocal support, a lever pivoted thereon and movable therewith and having a jaw at its end, a spring for forcing 125 130

the end of the lever opposite said jaw in a direction to withdraw the jaw, a roller mounted on the lever, and a stationary cam having two cut out portions and a high portion between them for engaging said roller and operating the lever.

17. In a plate finishing machine, the combination of a movable support, rollers carried thereby for supporting the lower edges of the plates, and a gripping device carried by said supports for gripping the edges of said plates outside the matter thereon.

18. In a machine for finishing stereotype printing plates, the combination of a frame, an arch thereon, supports on the opposite sides of said arch for the lower edges of the plates, a rock shaft for operating each support, positive means for connecting one rock shaft with its support, a link connected with the other rock shaft, a reciprocable member adapted to be operated by said link, and springs adjustably connected with said reciprocable member and bearing on the support on that side of the machine.

25 19. In a machine for finishing curved stereotype plates, the combination of a frame, a longitudinal shaft thereon, an arch on the frame, a stop outside the arch, means on the shaft for operating said stop, a stop on the opposite side of the arch, means on

the shaft for operating the second stop, and means within the arch for checking the motion of the plates therein.

20. In a plate finishing machine, the combination of a frame, an arch thereon, means for regulating the passage of plates along the frame, and resilient means in the arch for retarding the motion of the plates.

21. In a plate finishing machine, the combination of an arch, a frame having an inclined run-way thereon, anti-friction rollers in said run-way for supporting the edges of the plates, a stop located at the lower side of the arch, and resilient means within the arch for retarding the motion of a plate as it approaches the lower side of the arch.

22. In a plate finishing machine, the combination of a frame having an inclined run-way, anti-friction rollers along said run-way for supporting the plates, and a spring fixed to said frame and extending into position to retard the motion of the plates along the run-way.

In testimony whereof I have hereunto set my hand, in the presence of two subscribing witnesses.

H. A. WISE WOOD.
